UNITED STATES PATENT OFFICE

153,956

DESIGN FOR A SCREW CAP

John L. Lay, Ogden, Pa.

Application May 6, 1948, Serial No. 146,205

Term of patent 14 years

(Cl. D58—26)

To the Commissioner of Patents:

Be it known that I, John L. Lay, a citizen of the United States, residing at Ogden, Boothwyn Post Office, in the county of Delaware and Commonwealth of Pennsylvania, have invented a new, original, and ornamental Design for Screw Cap, of which the following is a specification, reference being had to the accompanying drawing, forming part thereof.

Figure 1 is a perspective of my screw cap looking from the top.

Figure 2 is a top plan view.

Figure 3 is a perspective looking from the bottom.

Figure 4 is a bottom plan view.

Figure 5 is a radial section.

I claim:

The ornamental design for a screw cap, substantially as shown.

JOHN L. LAY.
